RELEASABLE HOLDER FOR ROD

Robert L. Menegus, Wilmington, and Richard L. Akers, Claymont, Del., assignors to the United States of America as represented by the United States Atomic Energy Commission

Application June 30, 1954, Serial No. 440,577

3 Claims. (Cl. 294—102)

This invention relates to a releasable holding device and more particularly, to a device for holding an article suspended in such a way that the article cannot become accidentally dislodged from the device.

If an article is held in a holding device that releases the article by relative movement of one part of the holding device with respect to another, it may be important to prevent such relative movement when the device holds the object suspended in order that the article may not drop and thus do damage to itself or other articles.

An object of the present invention is to prevent release of a holding device when it is holding an article suspended. According to the invention, the relation of the device to the article in its suspended condition is such as to prevent release from the holding device.

Other objects will become apparent from the detailed description that follows and from the attached drawings, in which:

Fig. 1 is a vertical sectional view taken through the holding device of the present invention and of an article suspended from the holding device;

Fig. 2 is a horizontal sectional view taken on the line 2—2 of Fig. 1;

Fig. 3 is a vertical sectional view similar to Fig. 1 but showing the article in a self-supporting position and the device ready to be lifted away from the article; and

Fig. 4 is a vertical sectional view similar to Figs. 1 and 3 but showing the article and holding device ready for reengagement with one another.

The holding device of the present invention is designated by the reference character 10 and comprises a hollow inner member 11, a hollow outer member 12, a plurality of latching jaws 13, a plunger 14, and a plurality of balls 15. As indicated in Fig. 2, there are four latching jaws 13. There are four balls 15.

The hollow inner member 11 comprises a tubular section 16 and a rod 17 secured thereto by a pin 18 extending upwardly therefrom. The lower end of the tubular section 16 has two spaced circumferential ribs or flanges 19 and 20 which engage a groove 21 and a projection 22 formed on each latching jaw 13, whereby the jaws are supported from the lower end of the inner member 11 and depend therefrom so as to terminate in enlarged ends 23. This arrangement permits the jaws 13 to pivot on the projection 22 inward to grasp an article or outward to release it.

The hollow outer member 12 comprises a lower sleeve 24 and an upper sleeve 25 having a threaded connection therewith. The lower sleeve 24 has an internal circumferential rib 26 having a portion 27 of a certain internal diameter and a portion 28 of an internal diameter smaller than that of the portion 27. When as shown in Fig. 1 the holding device 10 supports an article 29 therein, the outer sides of the lower jaw ends 23 engage the large-diameter rib portion 27 of the outer member 12 and the juncture or shoulder formed between the rib portions 27 and 28, and the inner sides of the lower jaw ends engage a shoulder 30 and a juncture between this shoulder and a

head 31 both formed on the article 29 and is smaller in diameter than the head and larger in diameter than neck 32 formed below shoulder 30. The article head 31 has a reduced extension 33. Above projections 22 the jaws 13 have upward extensions 33a which in the released position of Fig. 4 are engaged by rib portion 28 to pivot the jaws sufficiently to clear the head 31.

The upper sleeve 25 of the outer member 12 has an internal shoulder 34 which in the position of Fig. 1 engages the upper end of the tubular section 16 of the inner member 11. Thereby downward movement of the outer member 12 with respect to the rest of the holding device 10 is limited to the position shown in Fig. 1 in which the jaw ends 23 are held by the rib 26 against the shoulder 30 of the article 29. Above the rib 26 the lower sleeve 24 has a portion 35 which is of larger internal diameter than the rib 26 and extends upwardly therefrom for a considerable distance, and a portion 36 which is of smaller internal diameter than the portion 35 and extends upwardly therefrom for a considerable distance. An internal shoulder 37 is formed on the lower sleeve 24 between the large-diameter portion 35 and the small-diameter portion 36.

The plunger 14 which is slidably mounted in the tubular section 16 of the inner member 11, has an upper enlarged head 39, a lower enlarged head 40 in the form of a ring threaded to the reduced lower end of the plunger, a portion 41 which is directly below the upper head 39 and has a diameter smaller than that of the upper head, and a portion 42 which is directly below the portion 41 and has a smaller diameter than the portion 41. A shoulder 43 is formed on the plunger 14 between the large-diameter portion 41 and the small-diameter portion 42.

The balls 15 are mounted in radial passageways formed in the tubular section 16 of the inner member 11, and their positions in such passages are determined by what portions of the plunger 14 and the outer lower sleeve 24 lie opposite the balls. When the parts of the holding device 10 occupy the position of Fig. 1, the balls 15 are engaged by the small-diameter portion 36 of the sleeve 24 and thus are forced to protrude inwardly enough so as to engage the shoulder 43 on the plunger 14 and thus to prevent the plunger from being depressed below the position of Fig. 1, in spite of the spring 44, which lies within the upper end of the tubular section 16 of the inner member 11 and reacts at one end against the rod 17 of the inner member 11 and at the other end against the upper head 39 on the plunger 14. In this position of the plunger the lower head 40 lies spaced from the lower end of the inner member 11 and the head extension 33 formed on the article 29.

When the article 29 and the holding device 10 are positioned as shown in Fig. 1 and the article is completely supported in the holding device and is without support from below, there is no way of accidentally dislodging the article from the holding device. The internal rib 26 on the outer member 12 holds the jaw ends 23 in and makes them form a space too small for the article head 31 to pass through. The outer member 12 cannot be moved upwardly with respect to the balance of the holding device 10, because engagement of the jaw ends 23 with the shoulder 30 on the article 29 prevents the jaw ends from moving inward, and thus the jaw ends cannot clear the small-diameter rib portion 28 on the outer member 12.

When the article 29 is to be released from the holding device 10, the article is raised by support applied to its lower end to the position of Fig. 3, in which the neck 32 of the article lies opposite the jaw ends 23 and the head extension 33 on the article engages the lower head on the plunger 14. The plunger is raised very slightly to relieve the pressure of its shoulder 43 against the balls 15 and

bring the small-diameter portion 42 opposite the balls 15. Now the outer member 12 can be and is lifted as shown in Fig. 3, because the jaw ends 23 can move inwards enough toward the neck 32 of the article 29 to permit the internal rib 26 of the outer member 12 to clear the jaw ends. When the outer member 12 is lifted sufficiently, an internal shoulder 45 formed by the upper end of the lower sleeve 24 of the outer member will engage an external shoulder 46 formed on the tubular section 16 of the inner member 11. At the same time as outer member 12 is lifted, the small-diameter rib portion 28 slidingly engages the jaw extensions 33a to pivot the jaw ends 23 clear of head 31. Further lifting of the outer member 12 will produce lifting of the entire holding device 10.

In the meantime the large-diameter portion 35 of the lower sleeve 24 will have been moved opposite the balls 15, with the result that they will have moved outwardly to permit the spring 44 to depress the plunger 14 sufficiently to bring the large-diameter portion 41 of the plunger opposite the balls 15, as shown in Fig. 4. Now the outer member 12 is held in raised position with respect to the balance of the holding device 10, because the balls 15, being engaged by the large-diameter portion 41 of the plunger 14, will not permit the outer member 12 to go below a position involving engagement of the balls with the shoulder 37 formed in the outer member 12.

When the article 29 is to be reengaged by the holding device 10, the holding device is lowered onto the article as shown in Fig. 4 so that the plunger 14 is raised because of the engagement of its lower head 40 with the head extension 33 on the article 29 sufficiently to bring the small-diameter portion 42 of the plunger opposite the balls 15. Now the balls may move inwardly, and the outer member 12 moves downwards with respect to the rest of the device to bring the small-diameter portion 36 of the outer member 12 opposite the balls 15 and the internal rib 26 down to the jaw ends 23, all as shown in Fig. 1. The article 29 is now reengaged by the holding device 10 and the plunger 14 is again in elevated position.

The intention is to limit the invention only within the scope of the appended claims.

What is claimed is:

1. A holding device for an article having at one end a head, a reduced neck, and a shoulder lying between the head and the neck and being larger in diameter than the neck and smaller in diameter than the head, said holding device comprising an inner member adapted to be positioned beyond said one end of the article and having a pair of spaced circumferential flanges, a plurality of latching jaws having grooves and projections engaging the flanges on the inner member and enlarged ends adapted to engage the shoulder on the article, and a hollow outer member containing the inner member and the latching jaws and longitudinally movable therewith, said inner member and said outer member being independently manipulatable and said outer member having an internal circumferential rib engageable with the enlarged ends on the latching jaws for holding them against the shoulder on the article.

2. The holding device specified in claim 1, the internal circumferential rib on the outer member having two portions of relatively large and small diameters, the article when suspended in the holding device having its shoulder and the juncture between its shoulder and its head in engagement with the enlarged ends of the latching jaws, said enlarged ends also engaging the large-diameter portion of the rib on the outer member and the juncture between the large-diameter portion and the small-diameter portion of the rib on the outer member, whereby engagement of the rib on the outer member with the enlarged ends of the latching jaws prevents outward

movement thereof and downward movement of the article out of the holding device, and engagement of the shoulder on the article with the enlarged ends of the latching jaws prevents inward movement thereof and upward movement of the outer member with respect to the latching jaws.

3. A holding device for an article having at one end a head, a reduced neck, and a shoulder lying between the head and the neck and being larger in diameter than the neck and smaller in diameter than the head, said holding device comprising a hollow inner member having a lower end spaced from the head of the article when carried by the device, a plurality of latching jaws supported by the lower end of the inner member and depending therefrom so as to terminate in enlarged ends engageable with the shoulder on the article, a hollow outer member having an internal circumferential rib engageable with the enlarged ends of the latching jaws, a first portion of larger internal diameter than the rib extending for a considerable distance above the rib, and a second portion of smaller internal diameter than the first portion extending for a considerable distance above the first portion, a plunger mounted in the inner member and having an upper head limiting downward movement of the plunger with respect to the inner member, a lower head positioned below the lower end of the inner member and within the latching jaws so as to be engageable with the head on the article, a first portion of relatively large diameter extending for a considerable distance downwardly from the head, and a second portion of relatively small diameter extending for a considerable distance downwardly from the first portion, means resiliently urging the plunger downwardly with respect to the inner member, and a plurality of circumferentially spaced balls mounted in the inner member so as to engage the first or second portion of the plunger and the second or first portion of the outer member, whereby support of the article from beneath independently of the holding device moves the article upwards so as to bring the neck of the article rather than the shoulder opposite the enlarged ends of the latching jaws, with the result that the same may move inwardly enough to permit the internal rib on the outer member to move upwardly beyond the enlarged ends of the latching jaws, which now may move outwards enough to permit the head on the article to clear the same and the holding device to be lifted off the article, and upward movement of the outer member takes said second or small-diameter portion thereof out of engagement with the balls and brings said first or large-diameter portion into engagement with the balls, with the result that the balls move outwards to permit the first or large-diameter portion of the plunger to move into engagement with the balls, now the large-diameter portion of the plunger holds the balls out to keep the outer member in raised position by preventing downward movement thereof beyond a position of engagement of the balls with the juncture between the small-diameter and large-diameter portions of the outer member, and lowering of the outer member is brought out by insertion of the article in the holding device sufficient to cause the head of the article to engage the lower head on the plunger and to raise the same to a position in which the small-diameter portion of the plunger comes opposite the balls.
